Primary Examiner — George D. Kirschbaum(74) Attorney, Agent, or Firm — Ashok Tankha(57) CLAIM

The ornamental design for a game table, as shown and described.

DESCRIPTION

FIG. 1 is a perspective view of the game table, showing the new design; and,

FIG. 2 is a top view thereof.

The broken lines of the figures illustrate environmental subject matter and form no part of the claimed design.

1 Claim, 2 Drawing Sheets三
